UNITED STATES PATENT OFFICE.

CHARLES A. McMANAMAY, OF BECKWITH, WEST VIRGINIA.

ROOF.

Application filed July 27, 1927. Serial No. 208,865.

The object of this invention is the provision of a roofing system, whereby a plastic roofing surface will be firmly anchored on a roof to present a shingle or like ornamental appearance.

A further object is the provision of anchoring means for plastic roofing surfaces that can be easily and quickly secured on roofs of varying designs, as well as on the 10 hips and valleys of such roofs, and which in addition to affording a firm anchorage for the roofing material, provides a means for ornamenting the appearance of such roofing and likewise holds the sheathing boards 15 in proper alinement and prevents the warping thereof.

A further object is the provision of a means for this purpose in which strands of wire are directed through clips of a simple 20 but novel construction, so that such strands may be shaped to represent tiles or shingles, and wherein the securing means passing through the clips cause the latter to bind or firmly grip with the wire strands and further wherein the strands afford projections 25 on the sheathing and produce ribs in the portion of the plastic roofing material arranged over and anchored to the strands.

For a full and comprehensive understanding of the invention, reference is to be 30 had to the drawings which accompany and form part of this application, and wherein:

Figure 1 is a top plan view of a sufficient portion of a building roof to illustrate the 35 application of my improvement thereon.

Figure 2 is a sectional view approximately on the line 2—2 of Figure 1.

Figure 3 is a sectional view approximately on the line 3—3 of Figure 1.

Figure 4 is a perspective view showing the manner in which the wire strands are 40 engaged by one of the clips.

Figure 5 is a plan view to illustrate a slight modification.

Figure 6 is a similar view showing the manner in which the strands may be secured in the hip or valley of the roofing.

The sheathing boards of the roof are indicated in the drawings, by the numeral 1. 50 Over the sheathing there is arranged the usual tar or roofing paper 2.

In carrying out my improvement I employ straight strands of wire 3 which are arranged transversely on the roof. 55 These strands 3 are passed through the rounded ends or ears 4 of metal clips 5. The

clips are formed of some suitable cheap material, such for instance, as tin. The ears are of a greater length than the cross sectional diameter of the strands 3 and for distinction the outer ends of the ears will be termed lips and are indicated by the numeral 6. The body of each clip has a central opening 7 therethrough, and if desired headed nails or the like 8 may be partly inserted through these openings and driven into the roof 1, when the clips are arranged in longitudinal series on the said roof. The clips of the alternating series are arranged intermediate of the series adjacent thereto, 70 as clearly disclosed by the drawings. When this is accomplished I train through the ears of the clips other strands of wire 9. These strands, when arranged in the clips may be of diamond-shape appearance, as disclosed 75 by Figure 1 of the drawings or the same may be shaped to present substantially rectangular members, as disclosed by Figure 5 of the drawings. In the last mentioned figure, the corners of the rectangular portions are disposed angularly. In this figure the wire strands are shaped to represent the usual formation of shingles. Of course, the wire strands 9 may be variously shaped in accordance with the aesthetic taste of the designer of the roofing but in each event the wires are so shaped as to present connected and projecting portions or what may be termed ribs for the plastic covering 10 of the roof. Before the plastic covering is arranged on the roof the headed nails or tacks 8 are driven fully home and the heads of these elements will contact with the lips 6 of the ear portions 4 of the clips and bend the said lips against the portions of the 80 strands received through the ears. In this manner it will be seen that the strands are effectively secured from movement in any direction. When the coating 10 is plastered over the roof the portions thereof disposed over the strands will be projected to form 85 the same with ribs so that the roof will have a shingle or like ornamental appearance. Primarily the improvement is designed as an anchoring device for slag roofings. It is 90 to be noted that with my improvement the tar paper is arranged upon the roof before the metal strands and that the metal strands are secured over the tar paper. Slag roofings have their foundations of melted tar 95 or pitch and while I have stated that the coating 10 is plastered over the roof, the 100 105 110

same in general practice is usually swabed thereover. The fixed foundation is comparatively thin after its application and the particular weave of wire strands provides 5 individual pockets for such foundation, and the strands themselves, being coated by the pitch present the roofing with a ribbed shape or formation as disclosed by Figure 1 of the drawings. After the pitch or tar 10 foundation is applied on the roofing and before the same is permitted to fully dry the roofing is sprinkled with sand, gravel or the like, and the same adhering to the foundation will assume a shape similar to 15 that of the foundation. However, if desired, roofing of other material may be troweled, such material being first placed in the pockets provided between the wire strands and a suitable troweling instrument 20 may be employed for troweling a roofing over the said strands to form the same with ribs and to give the said roofing an artistic appearance.

The strands 9 may be directed over the 25 hips and into the valleys of roofs, but if desired other longitudinal strands 11 may be secured by similar clips 12 and comparatively short strands 13 having offset ends 14 may be engaged in the second lips of the 30 said clips 12. The beaded ends of the clips 12 are contacted by the heads of the securing elements 15 to bind the same against the strands 11 as well as against the angle ends of the strands 13.

35 The improvement is of a simple nature, may be easily arranged on a roof, will afford a firm anchorage for the plastic outer coating of the roof so that such coating is held from buckling or bulging, and add to the 40 ornamentalty of the roof and provide an effective water shed therefor.

The improvement is designed to be constructed in rolls, say of a width equaling that of four shingles. The ears of all of the 45 clamps connecting the rolls, except the outer

ears of such clamps are bent into frictional engagement with the wire strands, and the clamps are omitted from one edge of the roll, so that the wires, at this edge of the roll may be received in the upstanding ears 50 of the clamps of the cooperating rolls. This permits of the improvement being laid on the roof in an expeditious manner. The gravel and sand of the roofing material may be tamped between the wire strands leaving 55 the strands and clips, of course, below such roofing material.

Having described the invention, I claim:—

1. An anchoring means for the plastic coating of a roof, comprising clips having 60 rounded ends to provide ears, wire strands directed through said ears and headed elements passing through the clips, entering the roof and contacting with the ends of the ears for bending the same into frictional 65 engagement with the wire strands, the spaces between the strands providing pockets for the roofing and the said roofing being rounded over the strands proper to provide rib-like projections for the roofing. 70

2. The herein described means for anchoring a plastic outer coating on a roof, comprising clips of bendable metal, each having rounded ends to provide ears which are projected inwardly and afford lips, said clips 75 being arranged in spaced longitudinal series on a roof, and the clips of one series being arranged intermediate of the clips of the adjacent series, all of said clips being held in place by a headed element which is partly 80 inserted therein, wire strands bent upon themselves to be received in the ears of the clips, and the headed elements thereafter designed to be fully driven home to bend the lips of the ears against such strands to cause 85 the said ears and lips to exert a frictional engagement against such strands.

In testimony whereof I affix my signature.

CHARLES A. McMANAMAY.
